UNITED STATES PATENT OFFICE.

WILLIAM M. REYNOLDS, OF PURCELL, COLORADO.

BEET-HARVESTER.

1,302,973.

Specification of Letters Patent.

Patented May 6, 1919.

Application filed May 22, 1918. Serial No. 235,972.

To all whom it may concern:

Be it known that I, WILLIAM M. REYNOLDS, a citizen of the United States, residing at Purcell, in the county of Weld and 5 State of Colorado, have invented certain new and useful Improvements in Beet-Harvesters; and I do hereby declare the following to be a full, clear, and exact description of the invention, such as will enable 10 others skilled in the art to which it appertains to make and use the same.

This invention relates to beet harvesters, and the primary object of the invention is to provide a novel form of beet uprooting 15 means which will uproot the beets and deliver them to a conveyer, with all of the tops of the beets facing in one direction.

More specifically, the object of this invention is to provide a beet harvester including an uprooting structure adapted for 20 use in connection with the elevating and topping structure disclosed in the application filed Nov. 30, 1917, Serial No. 204668, which includes a pair of uprooting blades 25 having their facing edges slightly spaced, which blades are provided with rearward extensions, that are curved, in the same direction, for engaging and guiding the beet tops so that the beets will be delivered to the 30 elevator with their tops extending in one direction.

With the foregoing and other objects in view this invention consists in such novel features of construction combination and arrangement of parts as will be hereinafter 35 more fully described illustrated in the accompanying drawings and claimed.

In describing the invention in detail, reference will be had to the accompanying 40 drawings wherein like characters designate like and corresponding parts throughout the several views and in which:

Figure 1 is a top plan of the improved harvester.

Fig. 2 is a fragmentary side elevation of the harvester, and

Fig. 3 is a detail top plan of the uprooting plow.

Referring more particularly to the drawings, 1 designates the supporting structure of the beet harvester, which is supported by a rear supporting axle upon which are mounted the usual type of supporting wheels 2 and by a front supporting axle 3 55 upon which are mounted supporting wheels

4. The supporting wheels 4 are swivelly connected to the frame 1, and the standards 5 which carry the supporting wheels 4 are slidably carried by suitable bearings 6 at the front ends of the main supporting frame 60 and these rods are adjusted through the medium of a rockably mounted hand lever 7 which has a segment 8 carried thereby that coacts with a rack 9. The rack 9 is connected to the bar 10, which connects the two 65 vertical rods 5.

The adjustment of the wheels 4 with respect to the frame 1 is provided to permit of the regulation of the elevation of the frame and consequently regulate the depth 70 of insertion of the uprooting plow 11 into the ground.

The uprooting plow 11 is carried by a suitable standard or supporting structure 12 and it comprises a pair of members 14 75 and 15 which have their inner edges slightly spaced as clearly shown at 16 in Fig. 3 of the drawings. The front ends of the blades 14 and 15 are reduced and sharpened as shown at 17, for insertion into the ground 80 to uproot the beets. The blade or section 14 of the uprooting plow has a rearwardly extending outwardly curving projection 18 formed upon the rear end of the same. The blade or section 15 of the uprooting plow 85 has a rearwardly extending projection 19 formed upon its rear end which is curved inwardly, or in other words is curved in the same direction as the projection 18. The projections 18 and 19 are provided for engaging the tops of the beets to direct all of the tops over toward the side of the elevator structure 20, corresponding with the blade or section 14 of the uprooting plow so that all of the tops will be properly positioned 90 to be engaged by the topping mechanism 21. The topping mechanism 21 is more specifically disclosed in the application filed Nov. 30, 1917, Serial No. 204,668.

A plurality of rods 22 are attached to 100 each of the sections 14 and 15 of the uprooting plow structure 11 and they extend rearwardly therefrom, for engaging and guiding the beets to the elevator structure 20, and also to permit dirt which might be clinging 105 to the beet bodies to fall therethrough.

In reducing the invention to practice, certain minor features of construction, combination and arrangement of parts may necessitate alterations provided such alterations 110

are comprehended within the scope of what is claimed.

What is claimed is:

In a beet harvester, an uprooting plow 5 comprising a pair of blades, projections formed upon and extending from the rear ends of said blades, said projections being curved to guide all of the beet tops in one direction, and a plurality of spaced tines at-

tached to and extending rearwardly from 10 each of said blades.

In testimony whereof I affix my signature in presence of two witnesses.

WILLIAM M. REYNOLDS.
